UNITED STATES PATENT OFFICE.

EDWARD P. SHARP, OF BUFFALO, NEW YORK.

TROLLEY-WHEEL.

No. 849,625.

Specification of Letters Patent.

Patented April 2, 1907.

Application filed June 29, 1904. Serial No. 214,664.

To all whom it may concern:

Be it known that I, EDWARD P. SHARP, a citizen of the United States, residing at Buffalo, in the county of Erie and State of New York, have invented new and useful Improvements in Trolley-Wheels, of which the following is a specification.

This invention relates more particularly to sectional or built-up trolley-wheels.

10 The object of my invention is the construction of a light, strong, durable, and inexpensive wheel of this type which is free from screws, bolts, and similar fastenings which are liable to get loose.

15 In the accompanying drawings, Figure 1 is a side elevation, partly in section, of a trolley-wheel embodying my improvements. Fig. 2 is a transverse central section thereof. Fig. 3 is a fragmentary view of the inner side 20 of the wheel-tim, showing the lugs for centering the tread and for preventing displacement of the side plates. Fig. 4 is a transverse section of the wheel, showing a modified construction thereof.

25 Similar letters of reference indicate corresponding parts throughout the several views.

A A' indicate the side or flange plates of the wheel, preferably stamped from suitable sheet metal and each provided with an integral web or central portion, preferably in the form of a spider B, as shown.

30 C is a tread-ring, of cast-copper or other suitable material, seated in the groove formed between the flanges of the side plates A A' and adapted to bear against the conductor or trolley-wire. (Not shown in the drawings.)

The side plates are provided at their inner edges with lugs or lips a, which extend inwardly across the joint between the plates 40 and serve to center the tread-ring with reference to the axis of the wheel. The lugs of one side plate preferably abut against those of the other plate, so as to hold the plates against circumferential displacement on each 45 other in both directions. For this purpose the lugs of each plate are arranged in opposing sets or pairs, and the lugs of one pair are properly spaced to engage one side of the contiguous lugs of the other plate, while the lugs 50 of the opposing pair are properly spaced to engage the opposite side of the companion lugs of the other plate, as shown in Fig. 1.

Although the lugs of the two side plates are offset when the plates are placed face to face, 55 as shown in Fig. 1, yet the plates are exact

duplicates and can both be stamped in the same dies.

As shown in Figs. 1 and 3, the tread-ring C is provided at its inner edge, on opposite sides of the pairs of lugs a, with stops or shoulders c, 60 which abut against said lugs, thereby interlocking the tread-ring with the flange-plates A A' and preventing circumferential displacement of the ring with reference to the plates.

D is the hub of the wheel, preferably provided at its ends with outwardly-extending flanges d and having a hollow central enlargement d', forming an annular oil-chamber.

E is a bushing fitted within the hub and adapted to turn on the usual axle, which is not shown in the drawings.

The rings or inner portions b of the spiders B surround the reduced end portions of the hub D and are permanently and rigidly secured thereto by casting collars or fillets F of any suitable metal around the end portions of the hub and the rings of the spiders, as shown in Fig. 2. The side plates are dished, 75 with their concave sides arranged toward each other, and the inner ring portions b of the spiders bear against the outer lateral edges or shoulders of the hub enlargement d', forming annular channels or spaces between 80 the inner sides of said rings and the enlargement, into which channels the molten metal flows, thereby securely embedding the webs in the cast collars. The collars are anchored upon the hub by the flanges d, over which latter the collars preferably extend, as shown, 85 to form a neat finish. In the construction shown in the drawings the bushing extends slightly beyond the hub at both ends, and the outer faces of the collars F are flush with the 90 ends of the bushing.

95 By forming the webs or spiders B integral with the side plates A A' and connecting the spiders with the wheel-hub by the cast collars all parts of the wheel are firmly united, 100 as the natural shrinkage of the metal tends to draw the parts closely together. This construction avoids the use of screws, bolts, or similar fastenings liable to become loose and materially reduces the cost of producing the 105 wheel.

110 In the modified construction shown in Fig. 4 the hub enlargement D' is separate from the hub D and constructed of substantially semicircular cross-section. This enlarge-

ment and the spiders B are united to the hub by cast collars F', similar to those of the first-described construction. If desired, these collars may be anchored to the hub by other means than the end flanges d. (Shown in Fig. 2.) For example, in place of these flanges the hub may be provided near its ends with external grooves or depressions d², into which the metal flows in casting the collars upon the hub, thus reliably interlocking these parts, as shown in Fig. 4.

While I have herein shown and described my invention as applied to a trolley-wheel, the same is also applicable to various other sectional or built-up wheels, such as sheaves and pulleys.

I claim as my invention—

1. A sectional wheel, comprising a hub, side plates having webs or central portions, and collars cast upon the hub and the adjacent portions of said webs, said collars and the hub being provided with interlocking portions which anchor the collars upon the hub, substantially as set forth.

2. A sectional wheel comprising a hub provided at its ends with flanges and between its ends with shoulders, side plates having webs or central portions surrounding the hub, and collars cast around the hub and the adjacent portions of said webs and confined between said shoulders and flanges, substantially as set forth.

3. A sectional wheel comprising a hub provided with end flanges and a central annular enlargement, side plates having dished webs surrounding the end portions of the hub and bearing against the outer lateral edges of said enlargement, leaving spaces between the outer sides of the enlargement and the inner

sides of the webs, and collars cast around the hub and the adjacent portions of the webs and between the webs and said enlargement, substantially as set forth.

4. A sectional wheel comprising a hub, opposing flange-plates secured to the hub and having lugs at their inner edges, and a tread-ring arranged between the flanges of said plates and having stops which engage said lugs, substantially as set forth.

5. A sectional wheel comprising a hub, and opposing flange-plates secured to the hub, each of said plates being provided at its inner edge with lugs which extend across the joint between the plates, substantially as set forth.

6. A sectional wheel comprising a hub, opposing flange-plates secured to the hub, and a tread-ring arranged between the flanges of said plates, said plates being provided at their inner edges with lugs which extend across the joint between the plates, substantially as set forth.

7. A sectional wheel comprising a hub, and opposing flange-plates secured to the hub and each provided at its inner edge with a pair of lugs which extend across the joint between the plates, one lug of each pair being arranged to bear against one side of the companion lug of the opposing plate and the other lug of the pair being arranged to bear against the opposite side of the companion lug of the opposing plate, substantially as set forth.

Witness my hand this 25th day of June, 1904.

EDWARD P. SHARP.
